CRANKSHAFT GRINDING MACHINE

Carl G. Flygare, Worcester, Mass., assignor to
Norton Company, Worcester, Mass., a corpora-
tion of Massachusetts

Application November 22, 1940, Serial No. 366,681

7 Claims. (Cl. 51—237)

The invention relates to grinding machines, and more particularly to a double head crankshaft grinding machine.

One object of the invention is to provide a simple and thoroughly practical, readily controllable crankshaft grinding machine. Another object of the invention is to provide a crankshaft grinding machine in which both ends of the shaft are rigidly clamped in opposed aligned work chucks. A further object of the invention is to provide a work head construction in which at least one of the work supporting and clamping chucks is arranged to float in an axial direction so as to prevent distortion of the shaft during a grinding operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of a crankshaft grinding machine embodying this invention, having parts broken away and shown in section, to more clearly show the construction;

Fig. 2 is a fragmentary vertical section, on an enlarged scale, through the right-hand work supporting head;

Fig. 3 is a cross sectional view, taken approximately on the line 3—3 of Fig. 2;

Fig. 4 is a cross sectional view, taken approximately on the line 4—4 of Fig. 2;

Fig. 5 is a fragmentary right-hand end elevation of the head as shown in Fig. 2, with the cover plate over the universal joint removed, taken approximately on the line 5—5 of Fig. 2; and

Fig. 6 is a fragmentary cross sectional view, on an enlarged scale, taken approximately on the line 6—6 of Fig. 2.

A double head crankshaft grinding machine has been illustrated in the drawings, comprising a base 10 which supports a transversely movable wheel slide 11 carrying a rotatable grinding wheel 12 on a wheel spindle 13 which is journaled in bearings (not shown) in the wheel slide 11. The wheel slide 11 is arranged to slide transversely on the usual V-way and flat way (not shown) on the base 10. The grinding wheel 12 may be rotated by any suitable source of power such as, for example, an electric motor 15 mounted on the upper surface of the wheel slide 11. The motor

15 is provided with a driving pulley 16 which is connected by a driving belt 17 with a pulley (not shown) mounted on the right-hand end of the wheel spindle 12.

5 A longitudinally traversable work supporting table 20 is arranged to slide longitudinally on a flat way and V-way (not shown) on the base 10 of the machine in a manner similar to that shown in the prior U. S. patent to Silven, No. 2,151,666 dated March 21, 1939, to which reference may be had for details of disclosure not contained herein. The work table 20 is provided with a rotatable work support which is preferably of a double head type comprising a pair of opposed aligned work heads 21 and 22 which in turn rotatably support work holding pot chucks 23 and 24, respectively. The pot chucks 23 and 24 are provided with pivotally mounted clamping jaws 25 and 26 rigidly to secure the opposite ends of a crankshaft in position in the chucks 23 and 24, respectively. The pivotally mounted clamping jaws 25 and 26 may be automatically operated by a power operated mechanism such as, for example, that shown in the U. S. patent to Silven et al., No. 1,837,342, dated December 22, 1931. As illustrated in the drawings, however, a manually operable clamping mechanism is provided, comprising clamping bolts 27 and 28, respectively, which clamp the jaws 25 and 26, respectively, to hold the opposite ends of a crankshaft to be ground rigidly in half bearing supports (not shown) formed in the pot chucks 23 and 24, respectively.

The pot chucks 23 and 24 are rotatably supported on heads 21 and 22, respectively, and are arranged to be synchronously rotated by means of an electric motor 30 mounted within the base of the machine. The motor 30 is provided with a driving sprocket 31 which is connected by means of a link chain 32 with a sprocket 33 which is slidably keyed to a rotatable shaft 34. The shaft 34 is rotatably supported in bearings which are fixed to and depend from the under side of the table 20. The opposite ends of the shaft 34 are provided with sprockets 35 and 36, respectively. The sprockets 35 and 36 are connected by link chains 37 and 38 with sprockets 39 and 40 synchronously to rotate the pot chucks 23 and 24, respectively.

50 In a crankshaft grinding machine, it is desirable to steady the work at a point opposite the operative face of the grinding wheel 12. Consequently a vertically movable steadyrest 41 is provided. The steadyrest 41 has not been illustrated and described in detail in the present applica-

tion since this steadyrest is not considered to be a part of the present invention. The steadyrest 41 is identical with the prior U. S. patent to H. A. Silven, No. 2,053,878, dated September 8, 1936, to which reference may be had for details of disclosure not contained herein.

In the grinding of crankshafts or other work pieces in a double head machine where the opposite ends of the work piece are rigidly clamped in supporting chucks, it is desirable that at least one of the work supporting chucks be mounted so that it may float axially in either direction so that even though excess pressure may be applied by the steadyrest 41 or the grinding wheel 12 or the pot chuck supporting bearing surfaces may be slightly out of line, the endwise floating movement of the chuck will allow the axis of the shaft to remain in the same relative position, thus enabling precise grinding of cylindrical portions on the work piece, such as the crankpins on a crankshaft.

As illustrated in the drawings, the right-hand work head 22 is provided with a floating mount for the pot chuck 24 whereby it may be moved axially in either direction to compensate for deflection in the work piece during the grinding operation. The pot chuck 24 is rigidly fastened to a flange 45 by means of a plurality of cap screws 46. The flange 45 is formed integral with a hollow spindle 47. The spindle 47 is rotatably journaled in bearings 48 and 49 in the head 22. It should be noted that the hollow spindle 47 is mounted so that there is a clearance between a shoulder 50 on the spindle 47 and the left-hand end of the bearing 48 and also a clearance between a collar 51 which is threaded onto the right-hand end of the hollow spindle 47 and the right-hand end of the bearing 49, thus providing sufficient lost motion so that the spindle 47 together with the pot chuck 24 may float axially in either direction during a grinding operation.

A yieldable device is provided normally to maintain the spindle 47 in a central position with clearance at either end thereof so that when a work piece has been clamped in an operative position in the chuck 24, the work piece together with the chuck 24 and the spindle 47 may float or move axially in either direction during a grinding operation. A sleeve 52 surrounds the spindle 47. The sleeve 52 is held against endwise movement relative to the spindle 47 by means of a pair of collars 53 and 54 which are locked in adjusted position on the spindle 47. The sleeve 52 is provided with two pairs of spaced downwardly downwardly projecting lugs 55 and 56 which straddle a pair of upwardly extending spaced lugs 57 and 58 which are fixed within the frame of the head 22.

A pair of angle iron members 59 and 60 are slidably supported between the lugs 57 and 58 in engagement with the pairs of lugs 55 and 56, respectively, which project downwardly from the sleeve 52. A compression spring 61 is interposed between the angle irons 59 and 60 and serves normally to maintain the angle irons 59 and 60 spaced from each other in engagement with the lugs 55-56 and 57-58, respectively. It will be readily apparent from the foregoing disclosure that any axial or endwise thrust on the hollow spindle 47 will serve through the lugs 55 and 56 to move either the angle iron 59 or the angle iron 60 toward the other, thus compressing the spring 61 so that the spindle 47 together with the pot chuck 24 supported thereby is free to

move or float axially in either direction during a grinding operation.

A drive shaft 65 extends through a central aperture 66 in the spindle 47. The left-hand end 5 of the shaft 65 is connected by a universal joint 67 which comprises a trunnion shaft or stud 68 passing through the shaft 65 and having its opposite ends journaled in bearings 69 and 70 mounted in a gimbal ring 71 of the joint 67. A pair of studs 72 and 73 are arranged diametrically opposite to each other and are supported by the flange 45. The inner ends of the studs 72 and 73 are supported in bearings 74 and 75, respectively, which are in turn supported in the gimbal ring 71, thus forming a universal joint connection between the drive shaft 65 and the flange 45 or the chuck end of the hollow spindle 47.

The driving gear or sprocket 40 is arranged to 20 transmit a rotary motion to the driving shaft 65 and through the universal joint 67 to rotate the sleeve 47 and the pot chuck 24. It is desirable that a suitable driving connection be provided 25 between the sprocket 40 and the right-hand end of the drive shaft 65 so that lost motion will be eliminated in the driving connection, and the connections being so arranged that the shaft 65 may readily float in an axial direction as governed by the spindle 47. A rotatable sleeve 80 serves 30 as a support for the driving sprocket 40 and the sleeve 81 formed integrally therewith. The sleeve 80 is slidably keyed by means of a key 82 with a rotatable sleeve 83 which is in turn supported by an anti-friction bearing 84. The bearing 84 35 is fixedly supported in a frame 85 which is either fixedly or rigidly supported on the work supporting table 20. The sprocket 40 and its integral sleeve 81 are slidably connected by a key 86 with a rotatable sleeve 87 which is in turn journaled in an anti-friction bearing 88. The bearing 88 is fixedly supported in the frame 85.

The sleeve 80 is provided with an integral flange 89 by means of which the sleeve 80 is 45 clamped in fixed relation with the sprocket 40 by means of a plurality of screws 90 which pass through elongated slots 91 and are screw threaded into the sprocket 40.

It is desirable to provide means whereby the 50 spindle 47 and pot chuck 24 may be rotatably adjusted to align the chuck 24 with the chuck 23. This may be accomplished by loosening the screws 90 and adjusting a pair of opposed adjusting screws 92 and 93 which are carried by 55 upwardly extending lugs 94 and 95 formed integral with the flange 89. The ends of the adjusting screws 92 and 93 are arranged to engage opposed faces of a stud 96 which is carried by the sprocket 40. It will be readily apparent from the foregoing disclosure that the sprocket 40 may be angularly or rotatably adjusted relative to the sleeve 80, after which it may be readily clamped in adjusted position by tightening 60 one or more clamping screws 90 (only one of which has been shown in the drawings).

A universal joint is provided between the rotatable sleeve 80 and the shaft 65. A universal joint housing 100 is slidably keyed on the sleeve 81 by means of a key 101. The universal joint housing 100 serves as a support for a pair of diametrically opposed studs 102 and 103. The inner ends of the studs 102 and 103 are journaled in bearings 104 and 105, respectively, which are in turn carried by a gimbal ring 106. The gimbal ring 106 is connected by a pair of

studs 107 and 108 with a sleeve 109 which is in turn keyed to the right-hand end of the drive shaft 65 in a manner to be hereinafter described. The studs 107 and 108 are fixedly mounted in the sleeve 109 and are journaled in bearings 110 and 111, respectively, which are carried by the gimbal ring 106, thus forming a universal driving connection between the driving sprocket 40 and the drive shaft 65.

In order to provide an adjustable slidable connection between the universal joint and the shaft 65, the sleeve 109 is a split sleeve having a plurality of slots 112, 113, 114, 115, 116 and 117 extending through the end portion at the right-hand end of the sleeve 109. The sleeve 109 is provided with a pair of tapered keyways 120 and 121 to receive a pair of driving keys 122 and 123, respectively. The keys 122 and 123 are shaped to fit within tapered splines 124 and 125, respectively, formed in the shaft 65. Adjusting screws 126 and 127 are provided at the ends of the keys 122 and 123. The adjusting screws 126 and 127 are screw threaded into the end of the sleeve 109. Adjustment of the keys in a direction toward the left will wedge the keys 122 and 123 into a rigid locked position securely to lock the sleeve 109 in adjusted position relative to the shaft 65. A locking collar 130 is screw threaded onto the right-hand end of the sleeve 109 and is provided with an internal tapered aperture which fits a tapered mating face on the split portion of the sleeve 109. By tightening the sleeve 130 after the parts have been adjusted to predetermined positions, the sleeve 109 together with the keys 122 and 123, respectively, may be locked in a rigid adjusted position relative to the shaft 65.

In order that the sleeve 80 together with the sprocket 40 and the universal joint housing 100 together with the parts carried thereby may float in an axial direction with the shaft 65, a yieldable connection is provided comprising a plurality of springs 132 which are interposed between apertures in a pair of spaced collars 133 and 134 which loosely fit within an aperture within the sleeve 81. The collars 133 and 134 together with the springs 132 are held in position by means of an end cap 135 which is fixedly mounted to the sleeve 81. The collar 133 is engaged by the right-hand end face of the sleeve 81 and the collar 134 is engaged by a shoulder formed on the universal joint housing 100. The integral sleeve formed with the housing 100 is held in position on the sleeve 80 against the end of the sleeve 81 by means of a collar 136.

It will be readily apparent from the foregoing disclosure that when the shaft 65 floats in a direction toward the left, the shoulder on the universal joint housing 100 will move the collar 134 toward the left, thus compressing the springs 132 so that the entire driving mechanism floats toward the left with the pot chuck 24, the hollow spindle 47, and the drive shaft 65. Similarly, if the chuck 24, hollow spindle 47, and shaft 65 float in a direction toward the right, the sleeve 81 which engages the collar 133 will compress the springs 132 during the floating movement of the parts toward the right. When the end thrust or pressure on the chuck 24 is released, the released compression of the spring 132 serves to return the parts to a central position so that they are again free to float in either direction, depending upon the thrust of the work piece upon the chuck 24 during a grinding operation.

It is desirable to provide a floating action for one spindle only and to utilize the other spindle,

namely, the left-hand spindle, supported in the work head 21 for rotating the chuck 23 so that it has no endwise floating adjustment. The construction of the left-hand work head 21 is substantially the same as the construction illustrated in Figs. 1 and 2 for the work head 22 except that the springs providing a yieldable float for the spindle are removed and end thrust means provided to hold the parts against endwise floating movement. Consequently, illustration is made only of the right-hand head construction.

It will be readily apparent from the foregoing disclosure that by locking opposite ends of the work piece to be ground in the pot chucks 23 and 24 and maintaining the pot chuck 23 against axial movement, the chuck 24 together with the parts associated therewith may readily float in an endwise direction, thus preventing undue distortion of the shaft during the grinding operation. Any deflection of the shaft may be readily absorbed by the floating movement of the spindle during the grinding operation, thus facilitating the grinding of precise cylindrical crankpins on a crankshaft.

The operation of this mechanism will be readily apparent from the foregoing disclosure. Assuming all of the parts to have been previously adjusted, a crankshaft to be ground is placed in position in the pot chucks 23 and 24 and the work clamping jaws 25 and 26 swung into place, after which the clamping bolts 27 and 28 are tightened to lock the jaws 24 and 26 rigidly to support opposite ends of a crankshaft being ground. The work rotation is then started and the pot chucks 23 and 24 synchronously rotated during the grinding operation. The steadyrest 41 is moved vertically into a supporting position opposite the operative base of the grinding wheel 12 and the grinding wheel 12 may then be moved toward the axis of the work piece to grind the same. The pot chuck 23 together with its supporting spindle are held against axial movement, which definitely locates the shaft in a predetermined position relative to the head 21 and table 20. The pot chuck 24 is arranged to float axially in either direction while being synchronously rotated with the pot chuck 23 which facilitates the compensation of any deflecting of the axis of the crankshaft from its normal path either due to its own weight or to the pressure of the steadyrest 41 or the grinding pressure of the grinding wheel 12.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a transversely movable rotatable grinding wheel and a longitudinally movable rotatable work support including a pair of spaced aligned work heads, a rotatable hollow spindle supported in each head, bearings in said heads for said spindle, at least one of said spindles being arranged to float axially in either direction, a work supporting pot chuck on each of said spindles, a driving shaft extending through said hollow spindles, a uni-

versal joint drivingly connecting one end of said shaft with the chuck end of said spindles, and means including driving connections adjacent to the other end of said driving shaft synchronously to rotate said pot chucks.

2. In a grinding machine having a transversely movable rotatable grinding wheel and a longitudinally movable rotatable work support including a pair of spaced aligned work heads, a rotatable hollow spindle supported in each head, bearings in said heads for said spindle, at least one of said spindle being arranged to float axially in either direction, yieldable means normally to maintain said spindle in a central position, a work supporting pot chuck on each of said spindles, a driving shaft extending through said hollow spindles, a universal joint drivingly connecting one end of said shaft with the chuck end of said spindles, and means including driving connections adjacent to the other end of said driving shaft synchronously to rotate said pot chucks.

3. In a grinding machine having a transversely movable rotatable grinding wheel and a longitudinally movable rotatable work support including a work head, a hollow spindle rotatably journaled in said head, a work holding pot chuck on one end of said spindle, an axially aligned rotatable hollow sleeve journaled in said head and spaced from said spindle, a driving sprocket on said second sleeve, a driving shaft extending through central apertures in said hollow spindle and sleeve, universal driving connections between one end of said shaft and the spindle, a sleeve slidably keyed to the other end of said shaft, and universal driving connections between said sleeves, said parts being arranged to facilitate an endwise floating movement of the pot chuck and spindle.

4. In a grinding machine having a transversely movable rotatable grinding wheel and a longitudinally movable rotatable work support including a pair of spaced aligned work heads, a rotatable hollow spindle supported in each head, bearings in said heads for said spindles, at least one of said spindles being arranged to float in an axial direction, a work supporting pot chuck on each of said spindles, a driving shaft extending through said hollow spindles, a universal joint connected between one end of said shaft and the chuck end of said spindles, and splined driving connections adjacent to the other end of said drive shafts synchronously to rotate said pot chucks.

5. In a grinding machine having a transversely movable rotatable grinding wheel and a longitudinally movable rotatable work support includ-

ing a pair of spaced aligned work heads, each of said heads having a rotatable work supporting chuck, at least one of said heads having a rotatable hollow spindle which is arranged to float in an axial direction, bearings for said spindle in said head, a hollow sleeve rotatably journaled in said head in axial alignment with said spindle, a driving shaft extending through clearance apertures in said spindle and sleeve, a universal joint connecting said shaft with the chuck end of said spindle, means positively to rotate said sleeve, and a second universal joint connecting said sleeve and shaft, said joint being slidably adjustable and drivingly connected with said shaft.

6. In a grinding machine having a transversely movable rotatable grinding wheel and a longitudinally movable rotatable work support including a pair of spaced aligned work heads, each of said heads having a rotatable work supporting pot chuck, at least one of said heads having a rotatable hollow spindle which is arranged to float in an axial direction, bearings for said spindle in said head, a hollow sleeve rotatably journaled in said head in axial alignment with said spindle, a driving shaft extending through a clearance aperture in said spindle and sleeve, a universal joint connecting said shaft with the chuck end of said spindle, means positively to rotate said sleeve, a second universal joint connecting said sleeve and shaft, splined driving connections between said universal joint and said shaft to facilitate longitudinal adjustment, and means to lock said splined connection in adjusted position relative to said shaft.

7. In a grinding machine having a transversely movable rotatable grinding wheel and a longitudinally movable rotatable work support including a pair of spaced aligned work heads, a rotatable hollow spindle supported in each of said heads, bearings in one of said heads for rotatably supporting the spindle and holding it against axial movement, bearings in the other of said heads for said spindle which are arranged so that the spindle may float axially in either direction, yieldable means normally to maintain said latter spindle in a central position, a work supporting pot chuck on each of said spindles, a driving shaft extending through said hollow spindles, a universal joint drivingly connecting one end of each shaft with the chuck end of each spindle, and splined driving connections adjacent to the other end of each of said driving shafts synchronously to rotate said pot chuck during a grinding operation.

CARL G. FLYGARE.
